UNITED STATES PATENT OFFICE

ROBERT J. McGHEE, OF VIRGINIA, MINNESOTA

SCRAPER

Application filed August 28, 1931. Serial No. 559,841.

This invention relates to mucking devices, and the embodiment here illustrated is particularly adapted for use in mining operations where drift or tunneling is practiced.

5 The principal object is to produce such a device which will aid materially in the process of mucking or caring for the material mined or removed in the process of tunneling.

10 More specific objects and advantages of the mechanism and method of operation will appear in the following description thereof.

Referring now to the accompanying drawing, forming part of this application, and 15 wherein like reference characters indicate like parts:

Figure 1 is an illustration of a portion of the interior of a tunnel, showing upon the bottom of same a common slush scraper 20 operatively associated with the invention.

Figure 2 is a side elevation of the scraper illustrating the method of operating the invention in conjunction therewith.

1 The 25 represents one of the side walls of the tunnel or drift, while 2 represents the face, and 3 the bottom thereof. 4 is a scraper or slusher, and which obviously may vary materially in form without departing from the spirit of the invention. In fact such a scraper may be on the forward end of a caterpillar tractor, car, or the like.

It is known to those versed in the art that in such a tunneling process where rock is encountered, the face is usually drilled in a 35 plurality of places and "shot", prior to which shooting an under cut such as indicated at 5 is frequently made so as to keep the bottom of the drift level, and insure easier work in the final mucking process after each shot.

Now my invention resides in providing a 40 novel instrumentality for assisting in the mucking process, and which comprises the placing upon the bottom of the tunnel intermediate of the forward end of the receptacle, carrier, or scraper 4, as the case may be, and the forward lower corner of the tunnel, which, as previously stated, may be within the under cut portion 5, a flexible apron, 45 in the instant case illustrated as a mat made

of wooden or metal strips 6 spaced apart and yieldably connected as by a link of chain or the like as at 7 adjacent the ends thereof, so that when the face of the tunnel is broken down the material will fall upon this mat as 55 clearly illustrated. The mat may be attached to the scraper at the forward corners thereof as by hooks or the like illustrated at 8 so as to insure its not parting readily from the scraper and yet easily detached therefrom 60 when desired.

At the forward opposite corners of the mat or apron may be attached a pulling line, or lines, as at 9, and which lines may be roven over sheaves 10 near the ceiling of the tunnel and led to power means of some sort common in the art but not illustrated; so that when the apron becomes loaded with muck, draft upon the lines 9 will roll up same, dumping the muck into the scraper as clearly shown in Figure 2, when the process may be repeated as desired, and obviously expedite materially the operation of mucking.

70 While I have shown this slat-like construction of apron, it is to be understood that the entire mat may be of interwoven chain, or combination metal and rubber linked material as is used for matting, or it may be entirely of rubber and/or canvas which would function in equally as good manner, the appearance of the mat, made of interwoven chain, being illustrated in Figure 2.

Having thus described my invention, what I claim and desire to secure by Letters Patent is

85 The combination with a mucking scraper, of a flexible apron for initially receiving the muck which is ultimately lodged in the scraper, means for attaching adjacent corners of the scraper and apron together, and means at the corners of the opposite end of the apron for rolling it backwardly towards the scraper.

90 In testimony whereof I affix my signature.

ROBERT J. McGHEE.
